UNITED STATES PATENT OFFICE.

RUDOLPH M. HUNTER, OF PHILADELPHIA, PENNSYLVANIA, ASSIGNOR TO
THE ELECTRIC CAR COMPANY OF AMERICA, OF SAME PLACE.

ELECTRIC RAILWAY.

SPECIFICATION forming part of Letters Patent No. 439,662, dated November 4, 1890.

Original application filed September 23, 1886, Serial No. 214,309. Divided and this application filed June 1, 1887. Serial No. 239,930. (No model.)

To all whom it may concern:

Be it known that I, RUDOLPH M. HUNTER, of the city and county of Philadelphia, and State of Pennsylvania, have invented an Improvement in Electric Railways, of which the following is a specification.

My invention has reference to electric railways; and it consists in certain improvements, all of which are fully set forth in the following specification, and shown in the accompanying drawings, which form part thereof.

This application is a division of my application, Serial No. 214,309, filed September 23, 1886.

The essential features of my system, so far as the conductors are concerned, lies in the use of suspended working-conductors arranged along the track. These conductors are bare, and may be made in the form of flexible cables, wires, or rods, and with which the traveling electric vehicle makes contact. These suspended conductors may be directly connected with the source of electrical energy or they may be connected indirectly thereto by means of fixed supply-conductors (preferably insulated) either supported above or below the ground, which supply and working conductors are connected at intervals by branch conductors. It is also evident that I may make the working suspended conductors in sections insulated from each other and connect said sections with the supply-conductors, as above specified, or said sections may be automatically cut out of circuit to prevent leakage, except when a motor or vehicle is in connection with the section. In fact, prior to the date of my invention suspended conductors for electric railways were not known. Hence I do not limit myself to the details of construction herein set forth.

In the construction specifically set forth for the overhead conductors I have shown them as suspended on counterbalancing-levers, so that the weight of the cables are substantially counterbalanced, and therefore may be termed "floating conductors." This has advantage in the fact that the contact on the motor or vehicle may be fixed and travel under the said conductors without excessive friction, thus not interfering with the speed of the vehicle. If two suspended conductors are employed, there will be two collectors; but, if desired, it

is evident that the rails may be used as a return-conductor.

Another part of my improvements has reference to the detection of leaks in the working-conductors. It is a difficult matter to prevent leakage of the current when using bared working-conductors—such as must be used in electric railways of this class—and the danger is greatest in underground conductors. This leakage is far less objectionable in systems using separate working and supply conductors than in systems using simply the working-conductors. In carrying out this portion of my invention I provide a shunt-circuit around the motor, connecting, preferably, with the two collectors, and in this shunt-circuit I place a resistance-changer and an electro-magnet whose armature controls an alarm-circuit, causing the alarm to ring only when the armature is not attracted by its magnet. The operation is that when the motor is normally running the resistance in the shunt should be so adjusted that the armature of the magnet contained therein is attracted and the alarm-circuit broken. If now the motor should run onto a section or portion of the working-conductor where the current was much diminished by loss, the resistance in the shunt would be far too great for the reduced current and the armature would fall, causing the alarm to ring and thereby call attention to the location of the leak and enable the same to be immediately attended to. External disturbances in the current, as trouble at the central station or change in the resistance of the motor-circuit, might cause the alarm to ring; but these would be exceptional causes and could be accounted for. A detector to indicate automatically the position of a leak is very important, particularly on long lines traversing uninhabited districts, as well as those of a damp nature.

In the drawings, Figure 1 is an elevation of an electric railway embodying my improvements. Fig. 2 is a sectional elevation of a portion of same, showing the details of the car and its connection with the working-conductors. Fig. 3 is a side elevation of the upper end of one of the supporting-posts, showing the method of suspending the working and supply conductors. Fig. 4 is a plan view of same. Fig. 5 is a cross-section through the

working-conductor and its clamp on line xx . Fig. 6 is a cross-sectional perspective view of one form of working-conductor. Fig. 7 is an elevation of the supporting-post and supply and working conductors, such as shown in Fig. 4, but with a switch device to put the working-conductor into circuit only when a vehicle is passing. Fig. 8 is a side elevation, showing the conductors in section, of a modified means of support for the cables or working-conductors. Figs. 9 and 10 are elevations showing two systems of arranging the sectional working-conductors, and Fig. 11 is a cross section through an electrically-propelled vehicle and the road-bed.

A are vertical posts of wood or metal and support the working suspended conductors B B', which may be secured to pivoted levers B², which may be weighted at b³ to counter-balance the weight of the conductor. These levers B² when used are hinged to a plate b², bolted or otherwise secured to the post A. The generator of electricity A' may be connected directly with these working-conductors or may be connected to supply-conductors b b, which are preferably insulated and permanently connected with the posts, which supply-conductors are electrically connected with the working-conductors either through the plates b² or the branch conductors b', whereby the supply and working conductors are connected at intervals along the line. The generator may be provided with means A², Fig. 1, to regulate the line-current. From this construction it will be observed that the working-conductors are free to rise and fall, in effect being counterbalanced or floated. The counterbalance-weight b³ is adjustable, so that the degree of counterbalance may be adjusted, and the lever B² is limited in its downward movement by suitable stops, such as in Fig. 3. Springs may be used, if desired, in place of the weights.

A³ are the rails of the railway upon which the electrically-propelled vehicle runs and are arranged parallel to the working-conductors. The car or vehicle is provided with a suitable support and contact-wheels or collectors C² C³, secured thereto and insulated from each other, and said wheels run under the conductors B B', receiving the current therefrom. The conductors are counterbalanced sufficiently to reduce the frictional contact to just what is necessary to make a good electrical contact, and as said wheels are higher than the normal highest position of the conductors the cables are slightly raised as the wheels pass along under them, as shown. The lever-connection also prevents the cable conductors from being dragged along the line, causing them to have a fixed relative longitudinal position with the road-bed.

In place of supporting the conductors by levers, as above described, the cables may be supported normally in the metal brackets A⁵, Figs. 8 and 11, to which brackets the supply-conductors b are secured. In this construc-

tion the rollers or collecting-wheels C² on the car lift the cables or conductors up clear of the brackets while passing under them and over the said brackets.

One method of joining the sections (when used) of working-conductors is shown in Sheet 2. The ends of the conductor-cables are bent into a loop or hook b⁶ and are placed in the similarly-shaped recesses between the clamping-plates B⁴, which are drawn together by bolts B⁶. It will now be observed by consulting Fig. 5 that the division-line between the clamping-plates at the bottom meet, as at b⁵, to form a continuous surface of contact and to prevent jarring of the traveling wheels. The ends of these clamps are tapered off to meet the conductors, as shown in Fig. 3. The clamp B³, so formed, is hung to the lever B² directly or through the mediation of a link b⁴. Where it is desired to simply support the conductor, the clamp may be substituted by a strap, as indicated in Fig. 7. If these sections of the conductor are not insulated from each other, then the working-conductor would be connected at intervals with the supply-conductor, if the same be used; but if the clamped ends be covered with an insulating material B⁵ then the working-conductor would be divided into sections, and each section could be connected to the supply-conductor by a branch wire b' or through one or more of the lever-connections. This latter construction is illustrated in Fig. 9, in which it will be seen that the lever and its clamp at 1 is insulated from both sections of working-conductor, while that at 2 is electrically connected to the conductor. In the construction shown in Fig. 10 one end of each section is insulated from its clamp B³, while the other end is not. Hence in this construction we would have a series of insulated sections each connected through its lever with the supply-conductor. Of course it is evident that these sections of working-conductors may be of any desired length, and may have as many or as few supports and connections with the supply-conductor as desired.

The conductor-cables may be simply light wire rods or cables of twisted metal wires, or they may be made as illustrated in Fig. 7, in which a core or center of steel B⁸ is coated with copper B⁹ by plating or dipping in a copper bath and the outer surface covered with a copper plate or wire twisted or wrapped about the said rod. The steel by this method will be proof against rust and will give strength to the conductor, enabling its section to be small for long spans. The outer copper coating forms a good contact with the collectors, and when worn may be replaced, and by having this steel core the outer covering may be used until worn almost completely off without weakening the conductors as a whole.

So far we have considered the working-conductors as permanently connected to the generator either direct or through the supply-

conductors. I would now refer specifically to the construction shown in Fig. 7. Here we have the supply-conductor normally insulated from the working-conductor or its lever 5 B^2 and combined with a branch conductor b' , terminating in a switch or circuit-breaker A^4 , arranged with respect to the supporting-levers B^2 , whereby when the levers are down the connection with the working-conductors 10 is broken; but when raised by a passing car then the levers will be raised and close the connection through the switch A^4 , supplying electricity to the sections of working-conductor brought in direct use. This arrangement enables the use of insulated supply-conductors and prevents excessive loss due 15 to leakage from the bared and exposed working-conductors. It is immaterial what form of switches be used, for they might be electrical—such as set out in my application, Serial No. 205,770 of 1886—or mechanical, such as herein set out.

There may simply be one suspended working-conductor, the rails being used as the 25 other conductor and, preferably, the return-circuit for the current. This construction is shown in Fig. 11.

Referring now to the construction of the passenger electric car or vehicle shown in 30 Sheets 1 and 2, D is a motor-frame preferably supported upon the car-axles d or their boxes, the car-body being in most cases supported on springs. To this frame D one or more electric motors D^2 are secured, all preferably 35 having the same shaft or armature-shaft, which is also preferably set on an incline. Carried upon the ends of this shaft are the worms D^4 , which mesh with worm-wheels D' on the axles d of the car, one of these worms 40 being above one worm-wheel and the other below the other worm-wheel. The obliquity of the armature or motor-shaft is not necessary, though desirable. To enable the motor to start up without having to overcome the 45 full resistance due to the inertia of the stationary car, I make the worms longitudinally movable upon the motor-shaft D^3 and provide springs d^2 upon each end and surrounding the shaft, though this particular arrangement of the springs is immaterial. It will be 50 seen that upon starting the rotation of the motor-shaft the first impulse of the worms would be to screw on or over the stationary worm-wheel, compressing the springs, and 55 thus gradually increasing the resistance to the revolution of the motor-shaft. This enables the motor to exert far greater power at starting, requiring a much smaller motor to overcome the inertia of the car than would 60 be required if the worms were fast upon the motor-shaft. It is evident that the worm should be sufficiently long to allow of this travel over the worm-wheel without running off the same. It is not necessary to have the 65 worms work against springs on both ends if there be two worms, for if a single spring is on opposite ends of these two worms then

either one or the other of said springs would take the thrust in starting the motor forward or backward. This last construction would 70 be as if we removed the spring d^2 on the left hand of the motor-shaft in Fig. 2.

Referring again to Fig. 2, E is the motor-circuit supplying current from the collectors to the motors. To enable the proper governing of all the motors most perfectly, I connect all of the armatures of the different motors, be they on one car or on one train, in one circuit E^2 and all of the field-magnets in another circuit E' , each provided with a current-indicator e . The armature-circuit E has a resistance-changer e^2 and a current-reverser E^3 , while the field-magnet circuit E' has its own resistance-changer e' and current-reverser E^4 . By this means the armature-circuit may be 85 regulated, cut out, or have its current reversed without affecting the field, and vice versa.

The construction of the motors shown in Fig. 2 is similar to that set out in my application, Serial No. 200,400, filed April 28, 1886, 90 in which the armature is stationary and the field-magnets revolve. The directions of the currents are indicated by the arrows.

O, Fig. 2, is a shunt-circuit around the motor, and is provided with a resistance-changer O^3 , and includes an electro-magnet O' . The resistance-changer O^3 may have an indicator o^3 to indicate the amount of resistance in this circuit. This circuit, which we will call a "detector-circuit," may be cut out by a switch o . The magnet O operates an armature O^2 , which is in effect a circuit-breaker arranged in an alarm-circuit N , including an alarm-bell N' , and, if derived from the motor-circuit, a resistance n to prevent an excess of 95 current passing through and destroying the alarm-bell magnets. This device is to detect a leak in the working-conductors due to grounding, and is particularly adapted to sectional working-conductors. The resistance O^3 is increased so that the magnet O' will just hold up its armature under the normal current. If now the motor run upon a section where the line-current is weak, owing to leakage or other defect, like short-circuiting, the 100 armature will fall and sound an alarm, indicating the position of the leak or defect. This armature might drop at other times when varying the resistance of the motor-circuit; but such causes would be readily understood, and no notice need be taken of them. It would be an easy matter to provide an 105 automatic device to prevent the alarm sounding upon cutting the motor out of circuit.

F, Fig. 2, is a secondary battery of a series 110 of cells, which may be coupled up in any desired manner in series or multiple (well known in medical and surgical batteries) to vary the power of said battery. This battery is charged by adjusting the switches Y so that the line-current passes partly over the circuit E^5 , charging the battery, the current from 115 which battery may be caused to pass over a lighting-circuit F^2 and light the electric lamp 120

- G, of the arc or incandescent type, at night. The strength of the current in circuit F² may be regulated by resistance-changer f', and the amount of current passing may be indicated by the current-indicator f². The lamp G shown is designated as a "head-light" and also to light the interior of the car by having its rays admitted through a frosted glass g in the forward and upper portion of the car-body.
- 10 G² is a small incandescent lamp for lighting the operator's platform, and is in a derived or shunt circuit G, derived from circuit F², and being provided with a separate resistance-changer g'.
- 15 The return-circuit might be a third rail B, (shown in dotted lines,) with which the collector C² would make contact. The railway may be lighted by lamps Q², either in shunt-circuit Q, connecting the supply-conductor, as shown
- 20 in Fig. 1, or as shown in Fig. 11, and these circuits may have suitable resistance-changers Q' to control the amount of current flowing through the lamp.
- 25 In conclusion, I would state that I do not limit myself to the details of construction, as they may be modified in various ways without departing from my invention, which comprehends, broadly, the constructions herein set out, the same being entirely novel at the date
- 30 of my invention, as far as I am aware.
- I claim—
1. In an electric railway, the combination of a suspended bared working-conductor supported from above, a supply-conductor connected to the working-conductor at intervals along the track, a source of electric energy to supply electricity to the supply-conductor, a traveling vehicle, tracks for said vehicle, parallel to said working-conductor, an electric motor on said vehicle, and a traveling collector moved by said vehicle and making contact with said suspended conductor.
  2. In an electric railway, the combination of a flexible and suspended bared working-conductor, a supply-conductor connected to the working conductor at intervals along the track, a switch device actuated by the passing vehicle to make connection between said supply and working conductors, a source of electric energy to supply electricity to the supply-conductor, a traveling vehicle, tracks for said vehicle, parallel to said working-conductor, an electric motor on said vehicle, and a traveling collector carried by said vehicle
  - 35 and making contact with said suspended conductor.
  3. In an electric railway, the combination of a flexible and suspended bared working-conductor, insulated supports therefor, a traveling electric vehicle, an electric motor on said vehicle, a current-collecting device carried by the vehicle, over which the working-conductor passes, the said collector raising the conductor and passing longitudinally under it during the travel of the vehicle, a supply-conductor to supply electric current to said working-conductor, branch conductors

connecting the supply and working conductors at intervals, and switches in said branch conductors to make or break the electrical connection between the supply and working conductors.

4. In an electric railway, the combination of a flexible and suspended bared working-conductor, insulated supports therefor, a traveling electric vehicle, an electric motor on said vehicle, a current-collecting device carried by the vehicle, over which the working-conductor passes, the said collector raising the conductor and passing longitudinally under it during the travel of the vehicle, a supply-conductor, branch conductors connecting said supply and working conductors at intervals, switches in said branch conductors, and devices carried by the traveling vehicle to operate said switches.

5. In an electric railway, a suspended and movable working-conductor, in combination with suitable pivoted counterbalancing devices to counterbalance the weight of the conductor, whereby it may be easily raised or lowered.

6. In an electric railway, a suspended and movable working-conductor, in combination with suitable counterbalancing devices to counterbalance the weight of the conductor, whereby it may be easily raised or lowered, a stationary supply-conductor, and electrical connections between said supply and working conductors.

7. In an electric railway, a suspended and movable working-conductor, in combination with suitable counterbalancing devices to counterbalance the weight of the conductor, whereby it may be easily raised or lowered, a stationary supply-conductor, and flexible electrical connections between said supply and working conductors at intervals along the line of the railway.

8. In an electric railway, a suspended and movable working-conductor, in combination with suitable counterbalancing devices to counterbalance the weight of the conductor, whereby it may be easily raised or lowered, a stationary supply-conductor, flexible electrical connections between said supply and working conductors at intervals along the line of the railway, and switches or circuit-breakers in said electrical connections, actuated by the rise and fall of said working-conductor.

9. In an electric railway, a floating or counterbalanced working-conductor arranged parallel to the tracks, in combination with means to adjust the amount of the counter-balance.

10. In an electric railway, two suspended bared working-conductors arranged one above the other and at different levels from the ground, in combination with a road-bed, a traveling vehicle, a motor on said vehicle, two collectors carried by the vehicle and making an electrical contact with said working-conductors, a motor-circuit on the vehicle, including said collectors, a field-magnet circuit,

an armature-circuit emanating from said motor-circuit, and a resistance-changer in each of said circuits.

11. The combination, in an electric railway, of two suspended and counterbalanced bared working-conductors, with two fixed supply-conductors connected with said working-conductors, a source of electric supply for said supply-conductors, a traveling vehicle, an electric motor on said vehicle, and an electrical connection between the motor and working-conductors.

12. In an electric railway, the combination of two flexible bared working-conductors, a supply-conductor connected with one of said working-conductors at one end, and an electric generator having one of its poles connected with the other end of the supply-conductor and its other pole connected with the opposite end of the other working-conductor.

13. In an electric railway, the combination of a flexible suspended working-conductor, counterbalancing-levers therefor arranged at intervals apart, and suspension-straps in which the conductor is supported and connected with the levers.

14. In an electric railway, the combination of a flexible suspended and movable working-conductor, counterbalancing-levers therefor arranged at intervals apart, conducting suspension-straps in which the conductor is supported to connect it with the levers, and a stationary supply-conductor electrically connected to said levers.

15. In an electric railway, the combination of a stationary or fixed supply-conductor, a counterbalanced suspended and movable working-conductor, counterbalancing-levers therefor arranged at intervals along the conductors, electrical connections between the supply and working conductors, and switches actuated by the counterbalancing-levers to make or break said electrical connections.

16. In an electric railway, the combination of a stationary or fixed supply-conductor, a counterbalanced suspended and movable working-conductor, counterbalancing-levers therefor arranged at intervals along the conductors, electrical connections between the supply and working conductors, switches actuated by the counterbalancing-levers to make or break said electrical connections, and suitable stops or supports to limit the downward movement of said working-conductor.

17. In an electric railway, the combination of a flexible and suspended bared working-conductor, insulated supports therefor, a traveling electric vehicle, an electric motor on said vehicle, a current-collecting device carried by the vehicle, over which the working-conductor passes, the said collector raising the conductor and passing longitudinally under it during the travel of the vehicle, a supply-conductor to supply electric current to said working-conductor, branch conductors connecting the supply and working conduct-

ors at intervals, devices carried by the traveling vehicle to operate said switches, and suitable stops or supports to limit the downward movement of said working-conductor.

18. In an electric railway, a suspended working-conductor, in combination with suitable counterbalancing devices to counterbalance the weight of the conductor, whereby it may be easily raised or lowered, a stationary supply-conductor, flexible electrical connections between said supply and working conductors at intervals along the line of the railway, switches or circuit-breakers in said electrical connections, actuated by the rise and fall of said working-conductors, and suitable stops or supports to limit the downward movement of said working-conductor.

19. In an electric railway, a floating counterbalanced working-conductor arranged parallel to the tracks, and suitable stops or supports to limit the downward movement of said working-conductor.

20. In an electric railway, two suspended bared working-conductors arranged one above the other and at different levels from the ground, and counterbalancing-levers for said conductors, in combination with a road-bed, a traveling vehicle, a motor on said vehicle, two collectors carried by the vehicle and making electrical contact with said working-conductors, and suitable stops or supports to limit the downward movement of said working-conductors.

21. In an electric railway, the combination of a road-bed, a suspended bared working-conductor made in sections and parallel to the road-bed, a clamp uniting the sections end to end, suitable supports for said conductor, a traveling vehicle independent of the conductor, a motor on said vehicle, and a collector working in contact with said conductor.

22. In an electric railway, the combination of a suspended bared working-conductor made in sections insulated from each other, clamps uniting the sections end to end, suitable supports for said conductor through the mediation of said clamps, a traveling vehicle, a motor on said vehicle, a collector moving with the vehicle and working in contact with said conductor, a supply-conductor, and electrical connections between said supply-conductor and sections of working-conductor.

23. In an electric railway, the combination of suspended working-conductor sections arranged end to end and insulated from each other, clamps mechanically uniting said sections together, suitable supporting and counterbalancing devices for said working-conductor sections, a supply-conductor, and electrical connections between said supply-conductor and sections of working-conductors.

24. In an electric railway, the combination of suspended working-conductor sections arranged end to end and insulated from each other, clamps mechanically uniting said sections together, suitable supporting and coun-

terbalancing levers connected to the said clamps, a supply-conductor, and electrical connections between said supply-conductor and sections of working-conductors.

- 5 25. In an electric railway, the combination of suspended working-conductor sections arranged end to end and insulated from each other, clamps mechanically uniting said sections together, suitable supporting and counterbalancing levers connected to the said clamps, a supply-conductor, and electrical connections between said supply-conductor and sections of working-conductor, including the counterbalancing-lever.
- 15 26. In an electric railway, the combination of suspended working-conductor sections arranged end to end and insulated from each other, clamps mechanically uniting said sections together, suitable supporting and counterbalancing levers connected to the said clamps, a supply-conductor, electrical connections between said supply-conductor and sections of working-conductor, a traveling vehicle, an electromotor on said vehicle, a collector carried by the vehicle and making contact with the working-conductor sections, and switches actuated by the passing vehicle through the agency of the counterbalancing-levers to make and break said electrical connections.
- 25 27. In an electric railway, the combination of suspended working-conductor sections arranged end to end and insulated from each other, clamps mechanically uniting said sections together, suitable supporting and counterbalancing levers connected to the said clamps, a supply-conductor, electrical connections between said supply-conductor and sections of working-conductor, a traveling vehicle, an electromotor on said vehicle, a collector carried by the vehicle and making contact with the working-conductor sections, and switches actuated by the passing vehicle to make and break said electrical connections.
- 35 28. In an electric railway, a suspended working-conductor made in sections, in combination with clamps uniting one end of each section with the other end of the next adjacent section, each clamp being electrically connected with one section and insulated from the next section, a supply-conductor, and electrical connections between said supply-conductor and said clamps.
- 45 29. In an electric railway, a suspended working-conductor made in sections, in combination with clamps uniting one end of each section with the other end of the next or adjacent section, each clamp being electrically connected to one section and insulated from the next section, a counterbalancing device for counterbalancing said working-conductor, whereby it may be easily raised, a supply-conductor, and electrical connections between said supply-conductor and said clamps.
- 55 30. The combination of a suspended con-

ductor B, made in sections having their ends bent over, as at b⁶, clamps B³, formed of side plates B⁴, uniting-bolts B⁶, and suitable suspending devices connecting with said clamps.

31. The combination of a suspended conductor B, made in sections having their ends bent over, as at b⁶, clamp B³, formed of side plates B⁴, uniting-bolts B⁶, insulation B⁵, insulating one of the clamped ends b⁶ from the clamp, suitable suspending devices connecting with said clamps, a supply-conductor b, and electrical connections b' between said supply-conductor and clamps.

32. In an electric railway, a vertically-movable suspended working-conductor, in combination with suitable counterbalancing devices to counterbalance the weight of the conductor, whereby it may be easily raised or lowered, and suitable stops or supports to limit the downward movement of said working-conductor.

33. In an electric railway, a vertically-movable suspended working-conductor, in combination with suitable counterbalancing devices to counterbalance the weight of the conductor, whereby it may be easily raised or lowered, a traveling vehicle, an electric motor on said vehicle, a collecting device carried by said vehicle and making contact with said working-conductor, adapted to raise the working-conductor as it passes longitudinally beneath the same, and suitable stops or supports to limit the downward movement of said working-conductor.

34. In an electric railway, a suspended working-conductor, in combination with suitable counterbalancing devices to counterbalance the weight of the conductor, whereby it may be easily raised or lowered, a stationary supply-conductor, flexible electrical connections between said supply and working conductors, arranged at intervals along the railway, switches or circuit-breakers in said electrical connections, actuated by the rise and fall of said working-conductors, a traveling vehicle, an electric motor on said vehicle, and a collecting device carried by said vehicle and making contact with said working-conductor and adapted to raise the working-conductor as it passes longitudinally beneath the same.

35. In an electric railway, a suspended working-conductor, a traveling electrically-propelled vehicle, and a contact device carried by the vehicle and making contact with said suspended conductor, the mechanical constructions being such that the contact and conductor automatically remain in contact irrespective of the irregularities in the suspension of the conductor.

In testimony of which invention I hereunto set my hand.
